TIRE

Raymond P. Hawkinson, Minneapolis, Minn., assignor to
Paul E. Hawkinson Company, Minneapolis, Minn., a
corporation of Minnesota

Filed July 29, 1968, Ser. No. 12,949

Term of patent 14 years

Int. Cl. D12—14

U.S. Cl. D90—20

FIG. 1 is a view in perspective of a tire showing my new design, it being understood that the tread design shown in full line is continued throughout the circumference of the tire, shown by dotted lines;

FIG. 2 is a fragmentary view in side elevation of one side thereof, the side opposite that shown being a mirror image;

FIG. 3 is a fragmentary transverse sectional view thereof as seen from the line 3—3 of FIG. 1, on a slightly enlarged scale; and

FIG. 4 is a fragmentary transverse sectional view thereof as seen from the line 4—4 of FIG. 1 on a slightly enlarged scale.

The dominant features of my design reside in that portion of the tire shown by full lines.

I claim:

The ornamental design for a tire, substantially as shown and described.
